THE NORRIS PETERS CO., PHOTO-LITHO., WASHINGTON, D. C.

UNITED STATES PATENT OFFICE.

JOHN GAPP, OF SCRANTON, PENNSYLVANIA.

TRACK-SANDING DEVICE.

1,102,577.

Specification of Letters Patent.

Patented July 7, 1914.

Application filed December 8, 1913. Serial No. 805,192.

To all whom it may concern:

Be it known that I, JOHN GAPP, a citizen of the United States, residing at Scranton, in the county of Lackawanna and State of Pennsylvania, have invented a certain new and useful Improvement in Track-Sanding Devices, of which improvement the following is a specification.

This invention relates to track sanding devices for locomotives, and is in the nature of an improvement upon that covered in my prior Patent No. 991,145, issued May 2, 1911.

One of the objects of my present invention is to provide a combined hand operated gravity feed and fluid pressure sander which may be readily applied to existing sand boxes, and having the gravity valves located outside of the sand box whereby they are readily accessible at all times for inspection, adjustment and repairs.

Another object is to provide an improved construction having a sliding connection or joint between the receiving chamber section and the sand discharge fitting whereby the latter part may be readily removed for cleaning or renewal without taking down the other parts of the device.

Another object is to provide an improved form of air jet connection whereby moisture and foreign particles will be deposited before the air enters the jet tube, and the latter may be easily cleaned when desired; and still another object is to provide an improved gravity valve for controlling the sand discharged by hand.

These and other features of my improvement are hereinafter more fully described and set forth in the claims.

In the accompanying drawings: Figure 1 is a perspective view of the exterior of a portion of a locomotive sand box showing one form of my improvement applied thereto; Fig. 2, a view partly in elevation and partly in vertical section showing a double sanding device embodying my improvement; Fig. 3, a plan of the same, the bolts being indicated in a section taken on the line 3—3 of Fig. 2; Fig. 4, a sectional view of a portion of the device, illustrating a slight modification; Fig. 5, a vertical section illustrating a single sanding device; Fig. 6, a section of the same taken on the line 6—6 of Fig. 5; Fig. 7, a sectional view illustrating a modified form of gravity valves and means for operating the same; Fig. 8, a view partly

in section, and partly in side elevation, illustrating a modification adapted to be located at a distance from the sand box, and having a pipe connection thereto; Figs. 9 and 10, 60 plans showing a modified form of gravity slide valve in the open and closed positions respectively; and Figs. 11 and 12, a plan and transverse section, on the line x—x, respectively, showing a further modification. 65

Many locomotives are now provided with a standard form of sand box, in which the bottom casing is downwardly inclined at the two sides and projects in the form of a flange, 2, having a plurality of sand outlet 70 passages, 2^a and 2^b, and a number of bolts, 3, for securing the air sanding device and clamping the flange thereof against the sand box, as shown particularly in Figs. 1 and 2 of the drawings. As shown in these 75 figures, the flange, 2, of the sand box is provided with four sand outlet passages for the double sanding devices, each having an air section, 1, containing the sand receiving chamber, 1^a, communicating with one of the 80 outlets, 2^a, and a sand delivery section, 7, containing a gravity discharge passage, 7^b, communicating with the outlet, 2^b, from the sand box. The section, 1, may be formed with a flange adapted to be fastened to the 85 sand box flange by means of the bolts, 3. Section, 1, is also provided with an air chamber, 4, to which the compressed air supply pipe, 5, is connected. This chamber, 4, serves as a separating chamber in 90 which moisture and other foreign particles contained in the air supply may be deposited and removed at convenient times by taking out the cleaning plug, 6, in the bottom of the chamber. The clean and dry air under 95 pressure passes through the opening, 4^a, from the top of chamber, 4, into an annular space, 4^b, around the nozzle, 10, which is provided with a perforation, 11, through its end and in line with the opening in the 100 sand receiving chamber. The air nozzle, 10, is preferably made in the form of a plug or spool, with both ends threaded, as shown, and adapted to be readily inserted into its position in chamber, 4^b, from the exterior of the casing or section. It may then 105 be easily removed for cleaning at any time.

The sand delivery section, 7, is connected to the section, 1, by means of a tapered nozzle, 7^c, having a sliding fit within the opening, 1^c, and containing a sand delivery passage, 7^a, communicating with the sand cham-

ber, 1^a, directly opposite the air jet nozzle, 11, and leading upward into the gravity discharge passage, 7^b. The section, 7, may be secured in position by flanges, 7^d, bolted to 5 the flange of section, 1, as shown in Figs. 1 and 2, or if preferred, it may be fastened directly to the flange of the sand box, as shown in Fig. 5, where only a single sanding device is employed. The sand receiving 10 chamber, 1^a, may be readily cleaned by removing the plug, 1^b, at the bottom, and the sand delivery section, 7, may be readily detached for cleaning, repairs, or renewal, by simply removing the bolts and sliding the 15 nipple, 7^e, out of the opening in section, 1. The pipe, 8, serves to conduct the sand from the discharge passage to the rails.

According to one of the features of my improvement, the gravity discharge 20 passages are controlled by hand operated sliding valves, 9, which are located outside of the sand box where they are readily accessible for inspection and repairs, and they are preferably located in recesses between 25 the flange of the sand box and the sanding device. The recess for the valves may be formed in the face of the flange of the sanding device, as shown in Figs. 2 and 3, or in the face of the sand box flange, as indicated 30 in Figs. 4 and 5, or they may be inserted in slots in the sanding device, as shown in Figs. 1 and 8.

As shown in Figs. 1 to 6 inclusive, the gravity valves are formed of flat L-shaped 35 plates, and pivoted at one end on the bolts, 3, the other end being attached to the operating rod.

In Fig. 7, I have shown a straight form of gravity valve, 9^a, mounted on an intermediate pivot in a recess extending upon 40 both sides of the valve whereby the same may be turned in either direction from its closed position for opening the gravity discharge passage. Any of the various forms 45 of valves may be operated directly by hand, or a small motor may be employed for this purpose, such as a cylinder, 12, having a piston, 13, and connecting rod, 14, actuated by fluid under pressure admitted by a pipe, 50 15, as shown in Fig. 7, and controlled by any suitable form of two-way or three-way cock.

Fig. 8 illustrates a modification of my improvement in which the sanding device is 55 formed with a sand chamber, 2^d, adapted to be located at a distance from the sand box, as for instance, beneath the running board, and connected to the sand box by means of a pipe, 2^e, or it may be connected close to the 60 sand box by a short pipe or nipple.

In Figs. 9 and 10, I have illustrated a reciprocating slide valve, 9^b, inserted in a longitudinal recess in the face of the flange for a double sander, and having ports, 9^c, 65 for communicating with the sand chambers,

1^a, and ports, 9^d, for controlling the gravity discharge openings, 7^b. Longitudinal slots are formed for the bolts, 3, in order to allow for the reciprocating movement of the valve. When the valve is in its normal position, the gravity ports, 7^b, are closed, as shown in Fig. 10, while the sand receiving chambers, 1^a, of the air jet section are fully open. When it is desired to apply sand directly by gravity, the valve, 9^b, is shifted to the position indicated in Fig. 9, in which the ports, 9^d, register with the gravity discharge passages, 7^b, allowing the sand to fall through the same, and the discharge pipes, 8, to the rails.

According to the modification shown in Figs. 11 and 12, the side valve, 9^e, is mounted in a recess formed in the face of an additional plate, 16, secured between the flanges of the sanding section, 1, and the sand box, 2, said valve being designed to normally close both gravity discharge passages, 7^b, but to be moved in one direction to open the gravity discharge of the forward sander, and in the opposite direction to open the gravity discharge of the rear sander. In order that the intermediate bolt, 3, may not interfere with the slide valve, 9^e, it may extend only part way through the plate, 16, which may have additional bolts upon the edge thereof at this point for securing the same to the sand box, as indicated particularly in Fig. 12.

With all of the various designs shown, it will be evident that the gravity valve is located outside of the sand box, where it is readily accessible at all times for inspection and repairs; that the sand delivery section, as well as the air jet nozzle, may be easily removed for cleaning or renewals; and that the improvement may be readily applied to existing standard sand boxes of locomotives in regular service by merely adjusting the usual fastening bolts.

Having now described my invention, what I claim as new and desire to secure by Letters Patent is:

1. In a track sanding device, the combination with a sand box having a plurality of sand outlets, of an air sander having a sand receiving chamber communicating with one of said outlets, and a gravity discharge passage communicating with another of said outlets, and a sand valve located outside of said sand box and controlling the gravity discharge passage.

2. In a track sanding device, the combination with a sand box having a plurality of sand outlets, of an air sander having a sand receiving chamber communicating with one of said outlets and a gravity discharge passage communicating with another of said outlets, and a sliding valve located outside the sand box and between the same and the gravity discharge passage.

3. In a track sanding device, the combination with a sand box having a bottom casting with a downwardly projecting side flange containing a plurality of sand outlet openings, an air sander section having a flange bolted to said sand box flange and containing a sand receiving chamber communicating with one outlet and a gravity discharge passage communicating with another outlet, and a sliding valve located between said flanges for controlling the gravity discharge passage.
4. In a track sanding device, the combination of a section containing a sand receiving chamber and having an air jet connection, and a sand delivery section having a gravity discharge passage, and a nipple connected to the air section by a sliding joint, the delivery section being provided with a flange for fastening said section in position.
5. In a track sanding device, the combination of a section containing a sand receiving chamber and having an air jet connection, and a delivery section having a flange detachably fastened to said air section and a nipple connected to said air section by a sliding joint, said delivery section containing a gravity discharge passage, and a delivery passage extending from the sand receiving chamber through said nipple to the gravity discharge passage.
6. In a track sanding device, the combination of a section containing a sand receiving chamber, a separating chamber having an air supply, an air chamber communicating with the separating chamber and the
- sand chamber, and jet nozzle inserted in said air chamber and containing a longitudinal bore for delivering air through said chamber.
7. In a track sanding device, the combination of a section containing a sand receiving chamber, a separating chamber having an air supply, an air chamber communicating with the separating chamber and the sand chamber, and a removable spool-shaped jet nozzle having ends fitting within the casing and containing a longitudinal bore communicating with said air chamber and discharging through the sand chamber.
8. In a track sanding device, the combination of a casing containing a sand receiving chamber and having an air jet connection, a gravity discharge passage also having a sand supply, and a reciprocating slide valve for controlling the supply of sand to the gravity discharge passage.
9. In a track sanding device, the combination of a casing containing a sand receiving chamber and having an air jet connection, a gravity discharge passage also having a sand supply, a longitudinal recess formed in the face of the casing at the sand supply passages, and a reciprocating slide valve in said recess and projecting at the end of the casing.

In testimony whereof I have hereunto set my hand.

JOHN GAPP.
